(57) **CLAIM**

The ornamental design for digital video disc player for automobile, as shown and described.

DESCRIPTION

FIG. 1 is a perspective view of front, left and top of digital video disc player for automobile showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating the unclaimed portions of digital video disc player for automobile and form no part of the claimed design. The broken lines immediately adjacent the shaded areas represent the bounds of the claimed design while all other broken lines are directed to unclaimed environment and are for illustrative purposes only.
